APPARATUS FOR BENDING TUBING

James H. Doyle, Malden, Ill., assignor to Harper-Wyman Company, Chicago, Ill., a corporation of Illinois
Filed Oct. 16, 1961, Ser. No. 145,040
3 Claims. (Cl. 72—388)

This invention relates to a method of and apparatus for making bends in tubing.

It is an object of this invention to provide a method of forming in tubing a very sharp bend characterized by an inner radius which is substantially equal to zero.

Another object of the present invention is to form such sharp bends near one end of a length of tubing while preserving both the uniform wall thickness and the uniform circular cross section of the tubing throughout, and thereby to produce a section of tubing highly suitable for use, for example, in forming venturi tubes for gas ranges.

It is a further object to form such a bend in a length of tubing with one single bending operation, thereby eliminating the expense involved in using several bending and shaping operations.

A further object is the provision of new and improved apparatus for carrying out the above referred to method.

More particularly, it is an object of the present invention quickly and cheaply to form such bends by first angularly trimming one end of a length of tubing, and then bending the tubing near the trimmed end.

In brief, the method of the invention includes the steps of trimming at least a substantial portion of one end of a length of tubing at an angle of between 30° to 60°, preferably 45°. The said end of the tubing is then bent by placing it upon a thumb tip mandrel projecting from a mandrel block which surrounds the exterior of the tube. The projecting end of the tubing is clamped by a clamping block. The blocks are then rotated relative to each other about a point opposite the curved part of the thumb tip mandrel to bend the tubing 90°. The mandrel blocks are so constructed, as with adjacent cutaway portions opposite the curved portions of the thumb tip, so that the blocks can be rotated the desired 90°.

Further objects of the present invention will appear from the following description, taken with the accompanying drawing, in which:

FIG. 1 is a perspective view of a length of tubing in which a bend has been formed in accordance with this invention;

FIG. 2 is an elevational view of a length of tubing at a preliminary stage in my method of bending tubing;

FIG. 3 is an elevational view of an alternative form of a length of tubing at the preliminary stage;

FIG. 4 is an elevational sectional view of the tube of FIG. 2 and of apparatus for forming the bend in the tubing;

FIG. 5 is an elevational view, partly in section, of the mandrel block, mandrel, and tubing of FIG. 4 taken along the line 5—5 of FIG. 4;

FIG. 6 is an elevational view, partly in section, of the clamping die, mandrel, and tubing of FIG. 4 taken along the line 6—6 of FIG. 4 preliminary to bending of the tube; and,

FIG. 7 is an elevational sectional view of the apparatus and tube of FIG. 4 at the completion of the bending operation.

Having reference to the drawing, FIG. 1 illustrates a length of tubing which has been formed in accordance with my invention with a right angle bend 12 having an inner radius 13 substantially equal to zero.

The sharp bend 12 is formed in a straight piece of tubing 14 of any desired length, in accordance with the

2

invention by a series of operations or steps, the first of which is best illustrated in FIGS. 2 and 3. One end of the tubing 14 is trimmed off at an angle as at 16. It has been found that in order to prevent the tubing from tearing during the bending operation, the plane of the trimmed end of the tubing may vary between about 30° to 60° from a plane normal to the axis of the pipe, an angle of about 45° being preferred. Alternatively, as in FIG. 3, it has been found that the tubing may be trimmed somewhat less than completely, as at 18, with a small part of the original end of the tubing remaining, as at 20. This alternative but still substantial trimming allows tubing to be conserved.

Referring to FIG. 4, the next step in the operation involves placing the trimmed length of tubing 14 in the bending apparatus, shown generally at 22. This bending apparatus includes a mandrel block 24, a mandrel 26, and two cooperating clamping dies 28 and 30 that are moveable to bend the tube.

The mandrel block 24 consists of two major portions, 32 and 34. The portions are provided with coaxial circular bores 36 and 38 of different diameters. The diameter of bore 38 is slightly larger than the outside diameter of tubing 14, so that when the tubing is inserted into bore 38, as is shown in FIG. 4, it may move axially. The diameter of bore 36 is such as to receive tightly the mandrel, which may be additionally secured, as by screws, not shown, to block 24.

Mandrel 26, as illustrated in FIGS. 4 and 5, extends axially through both bores 36 and 38 in sections 32 and 34 of the mandrel block 24 and has a head 40 projecting beyond block 24. The mandrel is a thumb tip mandrel, due to the configuration of its head 40, the purpose of which will be explained in connection with the bending operation.

As shown in FIGS. 4 and 6, the two cooperating clamping dies 28 and 30 are so constructed that when they are tightly pressed together by suitable means (not shown) they cooperate to define a circular bore 42 tightly securing the tube. Thus, it will be seen that when the two clamping dies 28 and 30 are separated, it is possible to slide the tubing 14 to the left as viewed in FIG. 4 through the clamping dies 28 and 30 and to insert the angularly trimmed edge 16 of the tube 14 a short distance into section 34 of mandrel block 24 so that the end portion of the tubing encircles a portion of the mandrel thumb tip 40. It will further be seen that when the two clamping dies are pressed together as in FIGS. 4 and 6, the tubing 14 will be tightly held against further movement. The clamping blocks may be mounted in known manner on suitable supporting structure 43 for movement between tube clamping and non-clamping portions.

After the tubing 14 has been so placed in the apparatus 22 and tightly fastened by clamping dies 28 and 30, the next step comprises a relative rotation of the blocks as by rotational displacement of clamping dies 28 and 30 and of the part of tubing 14 that is held by them from the position shown in FIG. 4 to the position shown in FIG. 7. By suitable means known to those skilled in the art the clamping dies 28 and 30 are arranged to rotate in a clockwise direction, as shown in the drawing, through an arc of 90° about the point indicated by the letter "a," as by rotation of the supporting structure 43. Mandrel block 24 and clamping die 30 are respectively provided with cooperating angularly 45° bevelled surfaces 44 and 46 to enable the clamping dies 28 and 30 to be rotated 90° relative to block 24. The point "a" in FIGS. 3 and 4 may be seen to coincide with the inner radius of FIG. 1.

As shown in FIG. 7, the effect of this rotational

movement is to provide tubing 14 with a sharp elbow or bend 12 having substantially a zero radius at the inner bend 13. It will be seen that due to the support given to the outside of the tubing 14 by the circular bores 38 and 42 in the mandrel block 24 and in clamping dies 28 and 30, the parts of the tubing on either side of the bend 12 are able to retain their original circular cross section. It will further be seen that the thumb tip 40 of mandrel 26 prevents the tubing from collapsing during the bending operation and maintaining the circular cross section of the tubing at the bend. Thus, it will be appreciated that the initial angular trimming of the tube 14 allows it to be bent very abruptly about the point "a" (or 13) without the tubing 14 tearing at the outside of the bend 12.

As can be seen in FIGS. 1 and 7, the resulting bend 12 in the tubing 14 is characterized by the fact that the inner radius of the bend 12 is substantially equal to zero. In order to achieve a bend of this extreme shortness it has been found necessary to place the tubing 14 within apparatus 22 so that the point on tubing 14 which lies directly above point "a" is along the shortest length of the trimmed tube 14 and is spaced away from the trimmed edge 16 of tube 14 a distance approximately equal to, and not greater than, the radius of the tube.

In order to prepare the bent portion of tubing 10 for its intended use it may be removed from the bending apparatus and trimmed or otherwise finished, as known and understood by those skilled in the art.

It will be appreciated that this illustration of my invention is simplified for clarity in the structure shown herein. It is to be understood that in actual operation fully automatic means may be applied to the execution of my method here disclosed, and that this is within the scope of my present invention. The drawing and the specification presented herewith constitute a full disclosure of my improved method of bending tubing in such clear and exact terms as to enable any person skilled in the art to practice the invention. Various alternatives, equivalents and modifications may be practiced without departing from the scope of the invention, which is defined by the following claims.

What is claimed as new and desired to be secured by Letters Patent of the United States is:

1. Apparatus for bending tubing to have substantially a zero radius at the inside of the bend including a mandrel block having a tube receiving opening at one end with a diameter slightly greater than the outside diameter of the tube and having concentrically disposed therein a thumb tip mandrel having a curved tip portion and an outside diameter slightly less than the inside diameter of the tube and with its tip portion projecting a fixed distance from the mandrel block corresponding substantially to the diameter of the tube, whereby an end portion of the tubing may be slidably received in said block, a tube encircling clamp block extending in one position from a point immediately adjacent the mandrel block and adapted fixedly closely to encircle and to hold tubing projecting from the mandrel block, said mandrel and mandrel block and said clamp block being relatively moveable to bend said tubing around the thumb tip mandrel about a point on the tube opposite the curved part of the thumb tip mandrel, said blocks abutting each other in said one position before the tube is bent and

having angularly cut away surfaces adjacent said point permitting said blocks to be moved substantially 90° about said point relative to each other, thereby to form a bend having a substantially zero radius.

2. Apparatus for producing a substantially zero radius bend in a length of tubing having a substantial portion at one end trimmed at an angle, said apparatus comprising a mandrel block having an opening for slidably receiving the trimmed end of the tubing, a thumb tip mandrel positioned within said opening and having a curved tip portion extending beyond the mandrel block a distance corresponding substantially to the diameter of the tubing, and clamping means for fixedly clamping said tubing adjacent said mandrel block in one position, said mandrel block and clamping means being rotatable with respect to one another about a point on the tube opposite the curved portion of the thumb tip mandrel, said point lying along the short dimension of the trimmed tube and spaced a distance approximately equal to and not greater than the radius of the tube from said short dimension trimmed end to form a bend in said tubing having an inner radius of curvature at said point of substantially zero.

3. Apparatus for producing a substantially zero radius 90° bend in a length of tubing having a substantial portion of one end trimmed at an angle of about 45°, said apparatus comprising a mandrel block having an opening at one end with a diameter somewhat greater than the outside diameter of the tubing, a thumb tip mandrel fixedly mounted in said mandrel block and disposed concentrically with respect to said opening whereby the trimmed end of said tubing may be slidably inserted around said mandrel and into said opening until a point on the short dimension of the tubing spaced a distance approximately equal to and not greater than the radius of the tubing from the short dimension trimmed end of the tubing lies at the mouth of said opening, said mandrel having a curved tip portion extending beyond said opening a distance corresponding substantially to the diameter of the tubing, and a tube encircling clamp block disposed in one position immediately adjacent said mandrel block for fixedly and closely encircling tubing projecting from said mandrel block, said mandrel and mandrel block and said clamp block being rotatable through 90° with respect to one another from said one position to draw said trimmed end of said tubing through said opening and to bend said tubing around the extending curved tip portion of the mandrel about said point on the short dimension of the tubing.
